(No Model.)

F. BURCKHARDT.

GRAIN HULLER.

No. 313,984.

Patented Mar. 17, 1885.

Attest,
Charles Pickles

Geo. L. Wheelock, T.

Inventor,

F. Burckhardt
By Knight Bros
Atty.

UNITED STATES PATENT OFFICE.

FREDRICH BURCKHARDT, OF ST. CHARLES, MISSOURI.

GRAIN-HULLER.

SPECIFICATION forming part of Letters Patent No. 313,984, dated March 17, 1885.

Application filed July 9, 1884. (No model.)

To all whom it may concern:

Be it known that I, FREDRICH BURCKHARDT, of St. Charles, in the county of St. Charles and State of Missouri, have invented 5 a certain new and useful Improvement in Grain-Hullers, of which the following is a full, clear, and exact description, reference being had to the accompanying drawings, forming part of this specification, and in which—

10 Figure 1 is a side elevation of my huller. Fig. 2 is a vertical section of the hulling portion of the same, one part of the cone being in side view. Fig. 3 is a top view of one-half of the cone and shell. Fig. 4 is a vertical section of the shell. Fig. 5 is an elevation of one 15 of the plates of the shell. Fig. 6 is a transverse section taken on the line 6 6, Fig. 2.

This invention relates to an apparatus more particularly intended for use in hulling corn 20 in the manufacture of hominy, grits, &c. It relates more particularly to an improvement on that form of huller shown in my application No. 148,915, filed November 16, 1884.

My improvement consists in features of novelty hereinafter fully described, and pointed 25 out in the claims.

A represents a conical form of huller provided with a shell whose inner portion has rows of tufts B, the lower part having double 30 the number of rows of tufts that the upper part has, for the purpose of increasing the hulling-surface. The huller-casing is preferably made in two parts provided with perforated lugs C, and secured together by bolts D. 35 The huller is supported by posts H or other suitable means. The tufts B, that act to break and hull the corn, are made of metallic brushes, as represented in Figs. 2, 4, and 6, and are arranged preferably in spiral form and held 40 in place by the material from which they are made, are bent and passed through the perforated plates I of the inner portion, and are held from coming out by wires J, and from passing in by the outer portion, L, of the shell. 45 One section or plate is shown in Fig. 5.

N are upper and lower rings to which the plates I are secured by screws O, (see Fig. 2,) and the plates may be further connected to the outer portion by screws P. (See Fig. 6)

50 These plates or sections are preferably provided with ribs T, as shown in Figs. 5 and 6, back of each upwardly-extending row of per-

forations. The ribs form backings to the brushes, supporting and making them more rigid.

U represents the cone or runner located within the shell and supported on a shaft, U', provided with a driving-pulley, U'', and an adjusting-lever, U³, and screw U⁴. The hulling-surface of this cone may also consist of metallic 60 brushes made and arranged the same as on the inner portion of the shell, or the same as shown in my application referred to herein.

The apparatus is preferably provided with a feed-hopper, V, or instead of the hopper the 65 material could be discharged into the machine directly from a spout or chute.

The casing and shell may both be secured to the rings N.

I claim as my invention—

1. In a huller, the combination, with a cone or runner having a hulling-surface, of a shell having rows of tufts increasing in number toward the bottom, and consisting of metallic brushes, substantially as and for the purpose 75 set forth.

2. In a huller, the combination, with a shell having a hulling-surface, of a cone or runner having rows of tufts increasing in number toward the bottom, and consisting of metallic 80 brushes, substantially as and for the purpose set forth.

3. A perforated huller-plate, I, having metallic brushes forming rows of tufts, and the ribs T, formed on said plate to provide backings or supports for the rows of tufts, as set 85 forth.

4. The combination of a cone having spiral rows of metallic tufts, and a shell having spiral rows of metallic tufts, said rows of tufts 90 increasing in number toward the bottom of both the cone and shell, as set forth.

5. The combination of a cone having a hulling-surface, and the shell, the latter consisting of inner and outer portions, upper and 95 lower rings, and spiral rows of tufts forming the hulling-surface, the inner portion being formed of sectional ribbed plates, and the rows of tufts increasing in number toward the bottom, as set forth.

FREDRICH BURCKHARDT.

In presence of—

GEO. H. KNIGHT,

SAML. KNIGHT.
